CLAIM

The ornamental design for a hand-held cleaning utensil with removable sponge head, as shown and described.

DESCRIPTION

FIG. 1 is a front perspective view of the hand-held cleaning utensil with removable sponge head attached to the utensil;

FIG. 2 is a rear perspective view of the hand-held cleaning utensil with removable sponge head attached to the utensil;
FIG. 3 is a side view of the hand-held cleaning utensil with removable sponge head attached to the utensil, the other side being a mirror image thereof;

FIG. 4 is top plan view of the hand-held cleaning utensil with removable sponge head attached to the utensil;

FIG. 5 is an underside view of the hand-held cleaning utensil with removable sponge head attached to the utensil; and,

FIG. 6 is a rear end view of the hand-held cleaning utensil with removable sponge head attached to the utensil.
